GEORGES LAKHOVSKY, OF PARIS, FRANCE.

HORN AND AMPLIFIER FOR SOUND-RECORDING AND SOUND-REPRODUCING APPARATUS.

Application filed February 24, 1923. Serial No. 621,036.

To all whom it may concern:

Be it known that I, GEORGES LAKHOVSKY, of 5 Avenue du Bois-de-Boulogne, Paris, France, engineer, have invented an Im-
proved Horn and Amplifier for Sound-Re-
cording and Sound-Reproducing Apparatus, of which the following is a full, clear, and exact description.

The horns or sound amplifiers, with which apparatus for recording and reproducing sound are usually provided, generally suffer from the disadvantage of having notes to which they resound and of producing resonance phenomena which alter the nature of the sound and more particularly of the voice.

This invention has for its objects an improvement in horns or sound amplifiers, in order to obviate the disadvantage indicated above.

This improvement is characterized essentially in that the horn is provided, over the whole of its height or over a part only, with a casing or jacket, there being left between this casing or jacket and the horn proper a space that contains a substance which forms a damper.

As substance forming a damper, use will preferably be made of a viscous or mucilaginous thick liquid, for instance oil, glycerine, a solution of gum, of gelatin, etc., or yet wax, paraffin, rosin, etc.

By means of the present invention the metallic vibrations of the horn are damped, and the sounds amplified by the horn are no longer subject to any deterioration.

The present invention is applicable to horns of any kind, shape and material.

In the accompanying drawing:

Fig. 1 is a view in elevation of a horn constructed according to the present invention.

Fig. 2 is a longitudinal section thereof.

Fig. 3 shows in vertical section another form of construction.

Fig. 4 illustrates a modification.

Fig. 5 shows in vertical section a photographic apparatus provided with an inner horn constructed according to the invention.

Fig. 6 is a detail view showing this horn in perspective.

As shown in Figs. 1 and 2 the horn proper *a* is provided with a casing or jacket *b*; the space between the horn *a* and this casing or jacket *b* is completely closed and contains a liquid *c*, preferably thick, viscous

or mucilaginous, for instance oil, glycerine, a solution of gum, gelatin, etc.

The horn can be provided with a filling plug *d* and a drain cock *e*.

In the form of construction illustrated in Fig. 3 the casing *b* is so shaped that the periphery of its flared part is beaded in a guard or keeper *a*¹ formed on the periphery of the horn proper *a*; at the other end, a lining or annular plug *f* is brazed or soldered between the narrow end of the horn and the end of small diameter of the casing.

On its flared surface, the casing is provided, as illustrated in Fig. 3, by way of example, with a filling up tube *d*¹ having a closing plug *d* and through which is introduced the damping liquid adapted to fill up the space between the horn *a* and the casing *b*.

The damping liquid might also be introduced in the space separating the horn from the casing after these latter have been connected together by beading of their flared edge and before placing in position and soldering of the lining or annular plug *f*, as illustrated in Fig. 4.

This liquid might again be introduced, after effecting the connection of the horn and casing and placing in position of the lining or annular plug *f*, by means of any opening provided in the casing and closed by soldering or any other means after filling up.

Figs. 5 and 6 shows the invention as applied to a phonographic apparatus provided with an inner horn; in this case, the latter is constituted in the following manner:

The horn proper *a* is provided on each of its faces with a casing *b* and the interval comprised between the faces of the horn *a* and those of this casing *b* is filled with a substance forming a damper as previously stated.

The casing *b* will be mounted on the horn *a* by any suitable means and the interval comprised between this casing and the horn will be closed by a plug *f* secured for instance by soldering after the filling up of this interval with the substance forming a damper.

This type of horn, in the shape of a frustum of a pyramid, might also be constituted by four panels having a double thickness with an inner filling by means of a substance

forming a damper as above set forth. The panels, of double thickness, being assembled by any known means (glue, nails, screws, etc.).

5. In a horn thus constructed, the layer of liquid surrounding the horn proper *a*, has for its effect to damp the metallic vibrations of the latter and to suppress the resonance-phenomena which occur, as has been mentioned above, in ordinary horns.

By employing the improved horn described above both in recording apparatus and in reproducing apparatus, the sounds and more especially the voice are recorded 15 and reproduced with a greater amount of purity and without losing their natural character.

According to the purposes to which the horn is to be applied, the casing or jacket 20 containing the damping substance may be extended over the whole height of the horn or over only a part thereof.

The improved horn or amplifier is applicable to all sound recording apparatus and 25 to all reproducing apparatus, such as phonographs, loud speaking apparatus and more especially those employed in wireless telephony.

It is obvious that the methods of carrying 30 the invention into practice described above are only given by way of example and that the dimensions, the shape and details of construction of this improved horn can be modified according to the different 35 purposes to which it is to be applied, as can also the material employed in the construction of the horn.

Claims:

1. A reinforcing horn for recording apparatus and sound reproducing apparatus, comprising a double casing and, in the space comprised between the horn and this double casing, a pasty material having for effect to damp the vibrations which might be trans-

mitted to the horn by the sonorous waves. 45

2. A reinforcing horn for recording apparatus and sound reproducing apparatus, comprising a double casing and, in the space comprised between the horn and this double casing, a pasty viscous material having for 50 effect to damp the vibrations which might be transmitted to the horn by the sonorous waves.

3. A reinforcing horn for recording apparatus and sound reproducing apparatus, comprising a double casing and, in the space comprised between the horn and this double casing, paraffin having for effect to damp the vibrations which might be transmitted to the horn by the sonorous waves. 55

4. A reinforcing horn for recording apparatus and sound reproducing apparatus comprising: a double casing beaded, on the one hand, in the flared edge of the horn and extending, on the other hand, up to the narrow end of this horn, in the space comprised between the horn and this double casing, a pasty viscous material adapted to damp the vibrations which might be transmitted to the horn by the sonorous waves, and an annular plug closing the annular orifice comprised between the narrow end of the horn and the end of the double casing. 60

5. A reinforcing horn for recording apparatus and sound reproducing apparatus comprising: a double casing beaded, on the one hand, in the flared edge of the horn and extending, on the other hand, up to the narrow end of this horn, paraffin filling up the space comprised between the horn and its double casing, and an annular plug closing the annular orifice comprised between the narrow end of the horn and the end of the double casing. 65

Signed by me this 1st day of February 70
1923.

GEORGES LAKHOVSKY.
